DOUBLE BED HAND OPERABLE KNITTING MACHINE

Wayne A. Current, Cranford, N.J., assignor to The Singer Company, New York, N.Y.

Filed May 3, 1973, Ser. No. 356,982

Term of patent 14 years

Int. Cl. D15—06

U.S. Cl. D47—5

Fig. 2

FIG. 1 is a front perspective view of a double bed hand operable knitting machine showing my new design, and FIG. 2 is a rear perspective view thereof.

I claim:

The ornamental design for a double bed hand operable knitting machine, substantially as shown.
